DOOR TEMPLATE

Jacob J. Hoven, 75 Meigs St., Rochester, N.Y.
 Filed Apr. 30, 1965, Ser. No. 452,078
 11 Claims. (Cl. 33—194)

This invention relates to a door template such as is used by carpenters in fitting a door to a door opening. Of course it may also be used in fitting windows to window openings, and the structure is called a door template merely for convenience of description, without intending thereby to limit it to use only in connection with doors.

An object of the invention is the provision of a generally improved and more satisfactory door template.

Another object is the provision of a template having especially advantageous and easy means for marking a door (or window) to the size to which it must be cut down in order to fit properly in the intended opening.

Still another object is the provision of a template sufficiently light to be easily handled in placing it in the opening which is to be measured and then in removing it from the opening and placing it on the door which is to be marked for cutting, and a template which is sufficiently simple so that the measuring parts can be manipulated and adjusted with the greatest ease.

A further object is the provision of a template so constructed that it can be very easily altered or modified on the job by an experienced carpenter, to enable it to be used with openings of larger or smaller size than the originally intended range of sizes.

A still further object is the provision of a template so designed that the carpenter using it can easily knock it down in a few moments to carry it compactly from one job location to another, and can reassemble or erect it in a few moments.

These and other desirable objects may be attained in the manner disclosed as an illustrative embodiment of the invention in the following description and in the accompanying drawings forming a part hereof, in which:

FIG. 1 is an elevation of a preferred form of template, showing it placed in a door opening in the manner in which it would normally be used to measure appropriate parts of the opening;

FIG. 2 is a section taken approximately on the lines 2—2 of FIGS. 1 and 3, on a larger scale;

FIG. 3 is a fragmentary plan of the parts shown in FIG. 2;

FIG. 4 is a fragmentary end view of one of the measuring members, showing the normal relation of the marking chisel to the surface which is to be marked; and

FIG. 5 is a view similar to FIG. 4, illustrating the action of the marking chisel under the impact of a hammer blow.

First to give some of the background of door templates (many forms of which are already known) a typical door opening is theoretically truly rectangular, and the same is true of a typical window opening. However, in actual practice it is found that the opening (especially a door opening) is often not quite of the theoretical shape. It may, for example, be slightly wider at the top than at the bottom, or vice versa, or the top member or header may not be truly horizontal, so that the opening is slightly higher on one side than on the other. The side members may be slightly sprung in or sprung out, making the opening slightly wider or narrower, at its mid-point, than at the top and bottom. Even if the opening is of

2

theoretically perfect shape and size, the correct dimensions (allowing for the necessary clearance) have to be marked on the door so that the door can be easily and quickly cut down to size, since doors are customarily made slightly oversize. Sometimes windows must also be cut down to size, but they are made oversize less frequently than doors.

The template of the present invention provides easy means for measuring the critical dimensions of the door opening or window opening as the case may be, and especially easy and convenient means for transferring the proper measurements to the face of the oversize door or window, enabling the door or window to be readily marked to show just where it should be cut to fit it to the intended opening.

Referring now to FIG. 1 of the drawings, a fragment of the wall is shown at 11, and the door frame is indicated in general at 13. The floor line is shown at 15. The template of the present invention, shown in normal measuring position in the door frame opening, includes a central vertical post 21 of light weight lumber, for example a piece of 1 x 4 lumber, of a length slightly less than the height of the door opening.

Secured crosswise against the back face of the member 21 are two cross pieces 23 at the top and 25 at the bottom of the vertical member 21. These cross pieces or cross arms 23 and 25 at top and bottom, respectively, may be identical with each other except reversed, one being in upside down relation to the other, and except for the fact that the top cross piece 23 may have its top edge flush with the upper end of the upright member 21, whereas the bottom cross arm 25 preferably has its bottom edge elevated slightly above the bottom end of the upright member 21, so that the upright member projects a short distance, say about one inch for example, below the bottom edge of the cross arm 25, as shown at 61.

Both cross arms 23 and 25 are preferably of light plywood of the shapes shown in FIG. 1, the top edge of the upper cross arm 23 and the bottom edge of the lower cross arm 25 being preferably straight and horizontal, while the bottom edge of the upper cross arm and the top edge of the lower cross arm are oblique as shown, to give each cross piece a greater bearing length on the vertical member 21. Both of the pieces of plywood are secured to the upright 21 by wood screws which are screwed in from the rear, first through the thickness of the plywood and then into the thickness of the upright frame member 21. Flat head wood screws are used, countersunk into the plywood, so that the screw heads do not project beyond the rear face of the plywood panels. One of the features of this construction is that there is nothing whatever (except the rubber blocks mentioned below) projecting beyond the rear face of the plywood panels, the rear faces being smooth so that they can be laid on a door which is to be marked, without scratching or otherwise damaging the door.

On each of the cross arms 23 and 25 there are adjustable measuring members or feelers, the arrangement being identical on each cross member, except that one is reversed or upside down with respect to the other, so that a description of one will suffice for both. There are two lateral feelers which are fairly long and have a long range of movement, and two vertical feelers near the outer corners, which have a much shorter length and shorter range of movement.

Referring first to the feeler 31, which is the left hand feeler extending horizontally on the top cross arm 23, this

feeler 31 is conveniently made of a strip of wood having a rectangular or square cross section, about one inch square more or less, with a slot 33 extending longitudinally along the center thereof, throughout most of the length of the strip 31. This strip is adjustably mounted on the front face of the cross arm 23 (that is, the face which is fastened to the upright member 21) to move horizontally along a guideway conveniently formed of sections of quarter-round molding 35 secured to the face of the plywood panel 23 in parallel spaced relation to each other to form a channel which receives the feeler strip 31 with a snug sliding fit. The quarter-round molding 35 may be secured to the plywood by screws, nails, or glue. A flat head screw 37, countersunk into the rear face of the plywood panel 23, extends through the slot 33 as shown more especially in FIG. 2, and has at its forward end a wing nut 39 which clamps down onto the forward face of the feeler strip 31 through an interposed washer 41. It will be readily appreciated from what has been said and from what is shown in the drawings, that when the wing nut 39 is loosened, the feeler strip 31 can slide readily along its groove or channel formed between the moldings 35, and when the wing nut 39 is tightened, the measuring strip or feeler strip 31 is clamped fast.

There is a similar arrangement on the right hand arm of the cross member 23, the feeler strip here being indicated by the numeral 31a, and the other parts (channel-forming quarter-round moldings, and clamping screw and nut) being arranged the same as those in connection with the left hand arm, and being designated by the same reference numerals. Another similar arrangement is on the bottom cross member 25, the left hand feeler member being designated by the numeral 31b and the right hand feeler member being designated by the numeral 31c, the channels and the clamping screws being the same as before.

In addition to the horizontally slidable feeler members 31, 31a, 31b, and 31c, there are also four vertically movable feeler members or measuring members of the same construction as the horizontally movable members just described, except that they are much shorter and have a shorter range of travel. The vertical feeler member at the upper left corner (when viewed as in FIG. 1) is designated by the numeral 32, that at the upper right corner is designated 32a, that at the lower left corner is designated 32b, and that at the lower right corner is designated 32c. Each of these is close to the respective end of the cross arm or cross member on which it is mounted, and each is slidable in its guiding channel formed by quarter-round strips, just as in the case of the longer feeler members previously described, the quarter-round molding strips and the clamping bolts and nuts all being designated by the same numerals used for the corresponding parts in connection with the longer horizontal feeler members.

At the outer end of each feeler member, both the long ones 31, 31a, etc., and the short ones 32, 32a, etc., there is a marking member such as a small chisel member 45 rigidly secured to the end of its respective slide member or feeler member as by screws 47, as shown particularly in FIGS. 2 and 4. It will be noted that the sharp chisel edge of each chisel member 45 faces rearwardly toward the rear surface of the plywood panel, and the sharp edge projects very slightly beyond the plane of the rear surface of the plywood panel. It will also be noted that the bevel of the chisel is away from the outer face of the chisel member 45, as seen in FIG. 2, so that the cutting edge of the chisel is spaced from the outer face of the chisel by a distance equal to the thickness of the chisel blade. This automatically spaces the cutting edge of the chisel in from the doorjamb by the thickness of the chisel blade, which is sufficient clearance for the edges of the door when the door is to be mounted in the door frame or jamb. It is also noted that the end of the chisel opposite to the cutting edge projects up above the upper

face of the feeler strip on which the chisel is mounted, when viewed as in FIGS. 2, 4, and 5.

Mounted on the under face of each feeler strip 31, 32, etc., tight against the inner face of the chisel, is a small block 51 of compressible resilient material such as sponge rubber, held to the rear face of the feeler strip as by means of strong adhesive. This compressible resilient material 51 is of such thickness that it is a little thicker than the amount by which the chisel projects beyond the rear face of the feeler strip on which it is mounted, and a little thicker than the thickness of the plywood panels 23, 25, and 63. Thus if the template is laid flat on a horizontally extending door or other similar panel, the various compressible strips 51, one associated with each chisel member, will hold the template elevated a slight distance above the face of the door panel on which the template rests, avoiding any premature marking or scratching of the door panel. But when the template has been positioned in the desired position on the door panel, then the upwardly projecting edge of each chisel member 45 can be hit in succession by a sharp blow of a hammer 55 as indicated schematically in FIG. 5, and the hammer blow will momentarily compress the resilient compressible material 51 associated with the particular chisel member 45 which has been struck, compressing it far enough so that the chisel point will make a slight mark on the door panel 57 on which the template is lying. Then when the template is removed, the various marks made by the various chisels which have been struck by a hammer blow, can be joined to each other by drawing a line along a straightedge, and the door can be cut down along the lines thus drawn. Then it will fit the door opening (with proper clearance formed by the thickness of the chisels) the first time the door is tried in the opening, and it is not necessary to fuss with it and shave it down little by little until it fits, as is necessary when one tries to hang a door without using a template.

The purpose of having the lower end of the upright frame member 21 project slightly below the lower edge of the cross member 25, is to be able to rest this lower end or projecting portion 61 (FIG. 1) on the floor 15, to support the device in an upright position in the door opening, without necessarily having the feeler members 32b and 32c touching the floor at this time. It may be desired to place a piece of threshold material or other suitable thickness gauge under each of the slide members 32b and 32c before adjusting it and clamping it in position, to determine the extent to which the door, when hung, is to have clearance from the floor, and this is easily done if meanwhile the structure is being supported by contact of the end 61 with the floor.

The construction being quite light, it is easy for the operator to hold it upright with one hand while he uses the other hand to adjust and clamp the upper horizontal feelers or slides 31 and 31a. When they have been clamped in position, with their ends (or rather, the respective chisels on their ends) tight against the doorjamb, friction will hold the template in its upright position in the door opening, resetting on the bottom projection 61, while the operator now has both hands free to complete the adjustment of the other slide members or feeler members. When adjustment has been completed, the operator pulls the template out of the door opening (since it is only held lightly by friction therein) and lays it down on the door panel which has meanwhile been positioned horizontally on a workbench or on sawhorses or other suitable support. He then taps each chisel member in succession with a hammer blow, as above explained, marking the door, subsequently joining the marks by drawing a line along a straightedge, and cutting or planing the door as needed. Until each chisel is hit with the hammer blow, it is held elevated slightly above the door by the resilient compressible material 51, so that the door is not marred

as the template is moved around on the door to position it in exactly the desired position.

The parts above described, with the two cross arms 23 and 25 at top and bottom, are all that is needed when the door frame is straight or true. However, if the door frame is warped or buckled so that it may be narrower or wider, intermediate its height, than at top or bottom, then one or more additional cross members may be used at any desired intermediate points on the frame member 21. FIG. 1 shows a third cross member 63, screwed to the vertical member 21 approximately midway of the length thereof, and substantially identical with the top cross member 23 except that it does not have the vertically movable slides or feelers. It does have two horizontally movable slides or feelers 31d and 31e, the same as the previously described slides 31, 31a, etc. If the sides of the door frame are not true, one or more intermediate gauging members like this will enable the door to be marked to cut it with slightly irregular side edges, so as to fit the irregular door opening.

If the device is to be used in fitting a door with a curved or arched top, several additional ones of the vertical slides 32 and 32a may be mounted on the upper cross arm 23, and they may be made longer so as to have somewhat greater range of travel, so as to fit against and properly measure the curved or arched upper end of the door opening (or the window opening, if a window is to be fitted). If the template is to be used repeatedly in connection with arched openings, it is best to have the series of upwardly extending feeler members diverging from each other like the spokes of a wheel, rather than having them parallel to each other.

The construction is extremely simple, and much lighter and easier to use than various prior door templates which are known in the art. Being made of relatively simple wooden parts, it is easily repaired on the job, if it is broken due to an accident. Moreover, when one job is finished and the template is to be carried to a different location, it is very easy and the work of but a moment to remove the wood screws which fasten the respective cross arms 23, 25, and 63 to the upright member, so that the two or more cross arms and the upright member can all be bundled together parallel to each other, for easy and compact carrying.

The template can be used with doors of a great range of widths, since the horizontal feelers are quite long and have a great range of travel. Also, if the template is to be used for a door of considerably different height from that for which the template was originally designed, this can easily be done. The simple vertical frame member 21 can be cut down to a shorter length if it must be used for a substantially shorter door, and the top cross arm may be repositioned thereon. A new vertical member 21 can be secured, of longer length, and the front faces of the plywood panel members 23, 25, 63 can easily be screwed to the rear face of the new and longer member 21, when the device is to be used with a taller door. Thus it is very versatile in the hands of any skilled carpenter.

It is seen from the foregoing disclosure that the objects and purposes of the invention are well fulfilled. It is to be understood that the foregoing disclosure is given by way of illustrative example only, rather than by way of limitation, and that without departing from the invention, the details may be varied within the scope of the appended claims.

What is claimed is:

1. A door template comprising a central upright strip of wood adapted to rest on the floor, a first crossarm of plywood having its front face fixed to the rear face of said upright strip near the top thereof, a second crossarm of plywood having its front face fixed to the rear face of said upright strip near the bottom thereof and spaced slightly above the bottom thereof so as to be elevated above the

floor when the bottom of said strip rests on the floor, guiding strips fixed to and projecting forwardly from the front face of each of said crossarms to form guide channels between pairs of parallel guiding strips, feeler strips 5 movable lengthwise along the respective guide channels so as to project one end of each strip to a variable extent beyond the crossarm on which it is mounted, and a clamping screw for clamping each feeler strip in a position in which it is adjusted in its channel, said channels and feeler strips being so placed that one feeler strip may project laterally beyond each end of each crossarm, two feeler strips may project upwardly beyond the upper edge of the upper crossarm, one near each end thereof, and two feeler strips may project downwardly beyond the lower edge of the lower crossarm, one near each end thereof.

2. A construction as defined in claim 1, further including a marking member mounted on the outer end of each feeler strip.

20 3. A construction as defined in claim 2, in which each marking member is a chisel.

4. A construction as defined in claim 1, further including a marking chisel mounted on the outer end of each feeler strip and having a sharp marking edge projecting 25 rearwardly from the feeler strip on which it is mounted and terminating slightly to the rear of the plane of the rear face of the crossarm on which the feeler strip is mounted.

5. A construction as defined in claim 4, further including a block of resilient compressible material mounted on 30 each feeler strip adjacent the chisel thereon and projecting rearwardly to an extent slightly beyond the sharp marking edge of the chisel, to hold the sharp edge of the chisel out of contact with a flat surface on which the template 35 is laid, until the block of resilient compressible material is compressed.

6. A door template comprising an upright frame member, a plurality of crossarms mounted on and extending crosswise of said frame member, one near the top and one near the bottom thereof, said crossarms having smooth flat rear surfaces adapted to lie against a flat door panel which is to be marked, a plurality of feeler members adjustably mounted on each crossarm for movement thereon to positions projecting outwardly beyond 45 the edges of the respective crossarms on which they are mounted, and a marking member mounted substantially at the outer end of each of said feeler members and adapted to make a mark on a door panel on which said template is laid, when the marking member is pressed 50 against such door panel.

7. A construction as defined in claim 6, in which said marking member is a chisel.

8. A construction as defined in claim 6, in which said marking member is a chisel having a rearwardly directed sharp edge extending substantially perpendicular to the length of the feeler member on which it is mounted, said chisel being beveled from its outer face to said sharp edge so that said sharp edge is offset inwardly from the outer face of the chisel by a distance equal to the thickness of 60 the chisel.

9. A construction as defined in claim 6, further including a body of compressible material mounted adjacent each marking member and having sufficient dimensions to hold the marking member normally spaced slightly from a door panel on which said template is laid, said marking member being capable of being brought into contact with said door panel to make a mark thereon when said compressible material is compressed.

10. A construction as defined in claim 9, in which said marking member has a striking portion adapted to be struck by a hammer to compress said compressible material to bring said marking member into marking relation to the door panel.

70 11. A door template comprising frame means, a feeler

adjustably mounted on said frame means to project to a variable extent beyond said frame means, a marking member mounted on said feeler substantially at the outer end thereof, said marking member having a mark-making end projecting transversely from said feeler, and a body of compressible material adjacent said mark-making end of said marking member and projecting slightly beyond said mark-making end to hold said mark-making end normally out of contact with an adjacent surface to be marked, said mark-making end being brought into marking contact with the surface to be marked by compressing said compressible material.
